[57] CLAIM

The ornamental design of a tie stake, as shown and described.

DESCRIPTION

FIG. 1 is a bottom, front perspective view of a tie stake showing my new design, the side opposite being a mirror image;

FIG. 2 is an enlarged top plan view thereof;

FIG. 3 is a bottom plan view thereof;

FIG. 4 is a front elevational view of a second modified embodiment of the design shown in FIGS. 1-4;

FIG. 5 is a left side elevational view thereof;

FIG. 6 is a right side elevational view thereof; and,

FIG. 7 is a rear elevational view thereof.
